Primary Examiner — Garth Rademaker

(74) *Attorney, Agent, or Firm* — Griffiths & Seaton PLLC

(57) **CLAIM**

The ornamental design for a plant stand, as shown and described.

DESCRIPTION

FIG. 1 is a top, front perspective view of a plant stand showing our new design;

FIG. 2 is an inverted, rear, bottom perspective view thereof; FIG. 3 is a right side view thereof, the left side view being identical to the right side view;

FIG. 4 is a front view thereof, the rear view being identical to the front view;

FIG. 5 is a top view thereof;

FIG. 6 is a bottom view thereof; and,

FIG. 7 is a top, front perspective view thereof shown stacked with an identical plant stand, which is illustrated in broken lines.

The features shown in broken lines depict environmental subject matter only and form no part of the claimed design.

1 Claim, 7 Drawing Sheets
